UNITED STATES PATENT OFFICE.

THOMAS B. REED, OF CARLTON, OREGON, ASSIGNOR TO J. W. BONES, OF CARLTON, OREGON.

ADJUSTABLE BEARING FOR JACKS.

1,129,014.

Specification of Letters Patent. Patented Feb. 16, 1915.

Application filed October 11, 1913. Serial No. 794,675.

To all whom it may concern:

Be it known that I, THOMAS B. REED, a citizen of the United States, residing at Carlton, in the county of Yamhill and State 5 of Oregon, have invented certain new and useful Improvements in Adjustable Bearings for Jacks, of which the following is a specification, reference being had therein to the accompanying drawing.

10 This invention relates to adjustable bearings for jacks, and has for its object the production of a simple and efficient means for firmly attaching the head to the jack in such a manner as to hold the body of the 15 jack at an angle to the head.

Another object of the invention is the production of a simple and efficient adjustable bearing which is so constructed as to allow the same to be readily adjusted upon 20 a jack in order to hold the jack at a set angle to the supporting head thereof.

Other objects and advantages of the present invention will appear throughout the following specification and claim.

25 In the accompanying drawings:—Figure 1 is a side elevation of the jack showing the adjustable bearing connected thereto. Fig. 2 is a section taken on line 2—2, of Fig. 1. Fig. 3 is a detail perspective of one of the 30 adjustable jaws adapted to hold the head of the jack in engagement with the body and plunger thereof.

By referring to the drawings it will be seen that 1 designates the body of the jack 35 which is provided with a knob 2 at its lower end, which knob is adapted to fit in the concave socket formed in the lower supporting head 4. This lower supporting head 4 is provided with a plurality of projecting teeth 5 which are adapted to grip a support for firmly anchoring the jack in a set position. A plurality of adjustable jaws 6 are carried by the inner face of the head 4, and these jaws are substantially 40 semi-circular, having transversely extending slots 7 formed therein for facilitating the passing of the bolts 8 therethrough, whereby the jaws 6 will be firmly anchored in engagement with the head 4. The inner 45 face 9 of each jaw 6 is concave so as to fit snugly around the knob 2 formed in the body 1 of the jack. It will, therefore, be

seen by carefully considering Fig. 2 that by having the jaws 6 away from the knob 2 the body 1 may be readily removed from the 55 head 4 when it is so desired.

It will be further understood that the jack as usual is also provided with a knob 27 similar to the knob 2, which knob 27 is carried by a vertically movable plunger. A 60 head 28 is carried upon the knob 27 and a plurality of adjustable jaws 30 similar in construction to the jaws 6 are connected to the lower face of the head 28 by means of the bolts 8 passing therethrough. It should 65 be understood that these jaws 30 are of similar construction relative to the jaws 6 above described.

It, of course, should be understood that any suitable or desired means may be employed for raising the plunger 11 which carries the knob 27.

It should be understood from the foregoing description that the heads 4 and 28 may be adjusted at different angles to accommodate themselves to a support and also to the object which is adapted to be elevated by means of the jack for the reason that the adjustable jaw 6 may be adjusted so as to firmly hold the body of the jack 1 at a 75 set angle to the head, and likewise the adjustable jaws 30 may also engage the knob 27 so as to hold the head 28 at a desired angle to the body of the jack 1.

What is claimed is:—

85 A ball and socket joint for a lifting jack comprising a knob, a head carried by said knob, said head provided with laterally adjustable clamping plates, said plates provided with aligned elongated transversely 90 extending slots, clamping bolts passing through said slots and engaging said heads for holding said plates in an adjusted position upon said head whereby said heads may be clamped in firm engagement relative 95 to said knobs, said plates provided with curved inner faces for fitting snugly in engagement with said knob.

In testimony whereof I hereunto affix my signature in presence of two witnesses.

THOMAS B. REED.
